UNITED STATES PATENT OFFICE.

THOMAS APPLEBY, OF PHILADELPHIA, PENNSYLVANIA.

ELECTROLYTIC-CLEANING ELECTRODE.

1,093,236.

Specification of Letters Patent. Patented Apr. 14, 1914.

Application filed June 24, 1913. Serial No. 775,465.

To all whom it may concern:

Be it known that I, THOMAS APPLEBY, a citizen of the United States, residing in the city and county of Philadelphia, State of Pennsylvania, have invented certain new and useful Improvements in Electrolytic Cleaning Electrodes, of which the following is a specification.

It is the object of my invention to provide in simple and inexpensive form, as a single article of manufacture, those parts essential to the practice of the electrolytic cleaning processes, hereinafter described, which are not generally available in a household, and by means of which ordinary metallic dishes or receptacles for the electrolytic solution may be used.

To this end my invention resides in the article of manufacture consisting of unitary insulating means and electro-positive element.

For an illustration of an embodiment of my invention reference is to be had to the accompanying drawing which is a sectional view through a container and the electro-positive element.

In the metallic container or conducting vessel M is disposed the electrolytic solution E consisting, for example, of a solution of sodium bicarbonate and common salt, sodium-chlorid.

P is the electro-positive element, such as a sheet or plate or block of electro-positive metal, such as zinc, to which is attached the insulating means I of any suitable material of any desired thickness or height.

The article to be cleaned, such as spoon S, is submerged in the solution E and brought into conducting contact with the plate P whereupon the electrolytic cleaning action ensues, removing any soiling coating upon the silver or other metal of the article S.

By the employment of my article of manufacture, the unit consisting of P and I, the process may be practised in any household by using any metallic dish such as M, the only apparatus to be purchased being the aforementioned article.

By the use of my article, it is not necessary to purchase a special dish or container M, and the process is available at a minimum of expense.

What I claim is:

1. As an article of manufacture, a unit consisting of an electro-positive electrolytic cleaning element and insulating material attached thereto for supporting said element in and electrically separating the same from a metallic container of electrolytic solution.

2. As an article of manufacture, a unit consisting of a zinc electrolytic cleaning plate and insulating material attached thereto for supporting said plate in and separating the same electrically from a metallic container of electrolytic solution.

In testimony whereof I have hereunto affixed my signature in the presence of the two subscribing witnesses:

THOMAS APPLEBY.
